HERBERT W. TRANTER, OF PETERBORO, ONTARIO, CANADA.

TOOL CONTROL FOR THREAD-CUTTING MACHINES AND METHOD OF MAKING SAME.

Application filed October 7, 1926. Serial No. 140,202.

The invention relates to improvements in the method and apparatus for making teeth of unusual configuration on worms, screws and other cylindrical mechanical elements of general application, and the invention particularly relates to an improvement in the method of forming a tooth on dies of the type used in forming helical corrugations in metal tubing.

10 It will be noted from the apparatus illustrated in the patents to L. H. Brinkman, Numbers 1,120,267, 1,120,268 and 1,120,269, granted December 8, 1914, that the corrugation forming die constituting the tool in such apparatus for forming corrugations in metal is usually in four sections, is provided with a bore sometimes of cylindrical form and preferably slightly tapered for receiving the metal tubing to be corrugated. The 20 complete bore formed when the sections are assembled for operation is provided with a helically formed thread or tooth. This tooth is peculiar in that it decreases in pitch from one towards the other end of the bore, and otherwise distinguishes from the usual uniform pitch of spiral teeth. In its use as a tool for corrugation of metal tubing it is required that the trough between the turns of the thread or tooth be of greater length 25 considered axially or lengthwise of the die and also flatter at the large end of the bore than at the opposite end. This peculiar form of thread is difficult to construct with the mathematical exactness required of dies 30 designed for the purpose herein outlined.

Attempts have been made to avoid the expense and inaccuracies heretofore characterizing the forming of such threads on die sections now in general use. One such suggestion has been to use separate blades inserted in slots in each of the die sections, as shown in the patent to Lewis No. 1,554,739, September 22, 1925. This structure has not proven satisfactory in that the blades are 40 flat while the required thread should be curved to the requisite taper with the result that there is a drag between the edges of the flat blades and the tubing inserted in which scraping of the blade edges has deleteriously 45 affected the final corrugated tubing.

The primary object of the present invention is to provide a simplified means which can be practiced economically to form a helical thread or corrugation forming tooth

of the type outlined, and which thread may 55 be formed integral with the body of the die or its composite sections easily and with mathematical exactness to any desired configuration, and in which any number of dies may be reproduced as facsimiles of each 60 other and in which all errors due to the personal equation of the operator are reduced to a minimum.

The invention features a method of cutting the work blank on an ordinary lathe or 65 similar screw cutting machine and thus avoid necessity of special machines for forming the variable sizes and types of dies necessary with the different sizes and configurations required in the finished tubing. 70

Broadly this phase of the invention is attained by substituting in the conventional lathe, a special form of lead screw in place of the usual uniform pinch lead screw common on such machines for controlling the 75 axial advance of the tool.

Another object of the invention is to provide a lead screw as a replaceable element of a screw cutting apparatus and which may constitute one of a set of such lead screws 80 each designed to control the advance of the thread cutting tool with a definite acceleration relative to succeeding units of time defined by the speed of rotary movement of the work in the lathe.

Still another object of the invention and featuring accuracy in the formation of the trough between adjacent turns of the thread or tooth in the finished die is to provide an arrangement of controlling grooves in the 85 lead screw which will insure the proper advance of the cutting tool relative to its preceding advance and this provides in a mechanical way for the proper degree of progressive narrowing of the trough from one 90 to the other end of the finished die.

Various other objects and advantages of the invention will be in part obvious from an inspection of the accompanying drawings and in part will be more fully set forth in 100 the following particular description of one form of device embodying my invention, and the invention also consists in certain new and novel features of construction and combination of parts hereinafter set forth and 105 claimed.

In the accompanying drawings,
Fig. 1 is a view largely diagrammatic of

a conventional form of thread cutting lathe provided with a lead screw particularly constituting the subject matter of the mechanical features of this disclosure;

5 Fig. 2 is an enlarged view in side elevation of the lead screw shown at 20 in Fig. 1; Fig. 3 is a similar view of a modified form of lead screw;

10 Fig. 4 is a view partly in axial section of a die machined by following the method and operation of the machine herein featured and taken axially of the finished work in the lathe on the line 4-4 of Fig. 5; and

15 Fig. 5 is a transverse sectional view taken on the line 5-5 of Fig. 4.

In the drawings and referring particularly to Fig. 1 there is shown a conventional form of screw or thread cutting lathe including a bed plate 10, tail stock 11, head stock 12, carrying a die section holding chuck 13 for carrying the die blank sections 14 of which four are shown in Fig. 5. Slidably mounted on the bed plate is the usual compound slide post 15 carrying an L-shaped 20 internal groove cutting tool 16. The post is mounted on a slide bar 17 and which bar is advanced in its bearing 18 by the engagement of a nut 19 engaging in slots in a lead screw 20. The lead screw is advanced in a 25 present time relation to the turning chuck 13 by gearing 21 connecting the lead screw with the head stock spindle 22. It is understood that the apparatus and parts thus far described are conventional and the showing 30 of a common form of screw lathe in Fig. 1 has been selected simply to illustrate one mechanism by means of which the invention herein featured may be practiced without necessity of providing special machines for 35 forming the desired variable pitch thread on the finished die, best shown in Fig. 4.

40 In place of the usual uniform pitch lead screw commonly found at 20 there is substituted a lead screw in which the groove 45 for receiving the nut 19 is formed with a variable taper and with a variable pitch of the order of the pitch and taper required of the thread on the finished die. One such form of lead screw is shown in Fig. 2 where 50 there is disclosed a groove 23 rectangular and substantially square in axial cross section and formed as a helix on the outer cylindrical face 24 of the screw. This helical groove is characterized by a uniform reduction 55 in pitch from the right towards the left end of the screw, the last turn 25 being in a plane perpendicular to the axis of the cylinder, indicated by the line a-b, and which axis is the axis of rotation of the cylinder 60 when mounted in operative position in the lathe as shown in Fig. 1.

65 In operation and assuming that the single groove lead screw shown in Figs. 1 and 2 is in operative control of the axial advance of the cutting tool 16, it will be understood

that with the tool disposed to extend into the bore 26 of the die sections assembled in the chuck, the tool will cut a groove, a variable pitch tooth of gradually reducing width considered axially and progressively reducing in length from one towards the other end of the bore in the die. The transverse shape of this groove of course will be that of the cutting end of the tool and it is preferable in practicing the method herein featured that the cutting edge be somewhat rounded and of course no wider than the width desired in the final flat turn 26 of the groove in the finished die.

70 When the first groove is cut the tool is withdrawn, the operation repeated if necessary until the desired depth of cut or rather approximately the desired depth of cut has been formed in the die. It will be appreciated that this operation will form a groove 75 of uniform width or rather length when considered axially while the required groove in the finished article is widest at the right hand side of the bore as shown at 27 in Fig. 4 and gradually diminishes in width to the 80 minimum width in the final turn of the groove 26 as shown at the left of Fig. 4. In order to form this type of groove it is necessary to progressively cut back into the material between the turns of the groove making 85 the greatest depth of cut at the right hand end of the bore as shown in Fig. 4 and diminishing the cut towards the left end of the bore and at the same time it is required, 90 of course, that the taper of the cut be maintained as initially formed.

95 This may be attained in two ways. When a single groove lead screw of the type shown in Fig. 2 is used, the work is bodily rotated slightly or indexed about its own axis c-d preferably by unmeshing the gear train 105 21, turning the work by hand over a few degrees of turn and remeshing the gears. In making this adjustment of the work, the nut 19 has not been disturbed from its position 110 engaging the groove 23. The machine is started and the operation repeated as previously described. This indexing of the work relative to the lead screw is continued until there remains between the succeeding 115 turns of the machined screw the sharp edged tooth shown at 28, Fig. 4. If the indexing of the work has been made over relatively small angular turns the trough of the groove 120 28 will be substantially smooth but should a greater degree of smoothness be required, a conventional form of grinding tool may be substituted for the cutting tool herein illustrated and the operation repeated as has been described for the actuation of the cutting tool.

125 Instead of depending upon the operator to index the work in order to gauge out the surplus material not required between the 130 turns of the finished thread on the die a

form of multiple groove lead screw 30 such as is shown in Fig. 3 may be substituted in the lathe for controlling the tool advance.

Referring to Fig. 3 it is noted that the cylinder 31 of the screw 30 is provided with three grooves 32, 33 and 34, each of which has a progressively decreasing pitch as has been described for the single groove screw 23 shown in Fig. 2. Succeeding turns of adjacent grooves have gradually reducing pitch from right to the left end of the screw and all of the grooves finally merge into a substantially flat groove 35 at the left end of the screw.

15. In operation with the form of control screw shown in Fig. 3 in control of the tool, the nut 19 is first positioned in groove 32 and a correspondingly pitched groove is formed in the die in the manner heretofore 20 described in connection with the formation of the groove when under control of the single groove screw shown in Fig. 2.

Instead of indexing the work as previously described, the operator next inserts the 25 controlling nut 19 into the second groove 33 and the cutting operation is repeated as described for the cut formed when the nut was in the first groove 32. It is understood that this second cutting operation will widen the 30 groove as at 27 a maximum amount at the right hand end of the die and gradually reducing in its cutting width towards the left end of the die; the tool finally moving into the flat turn 35 previously cut when 35 the tool was under control of the groove 30.

The nut is then positioned in the third groove 34 and the operation repeated as previously described, the tool cutting a little wider channel; a maximum amount at the 40 right and a minimum amount at the left of the die. It is understood that the controlling lead screw may be provided with any number of grooves of the type of the grooves 33, 34 and 35, but in actual practice it has 45 been found that three grooves are sufficient to give the desired configuration to the grooves which form the thread in the completed die.

The finished die formed of the die sections and mounted in the chuck as shown in Figs. 4 and 5 is in turn mounted in a machine and metal tubing 36 fed therethrough to form the corrugations 37 following conventional practices in this respect.

55. By following the means herein suggested in the machining of dies for corrugating metal tubing, it has been possible to form the variable pitch threads required in such dies with mathematical accuracy and there 60 is formed either a continuous thread in an integral die blank or a continual thread in the sectional die blanks illustrated. In either case the thread can be of the theoretical accuracy required of dies used in forming corrugations in thin metal tubing. The

operation of forming such dies has been reduced to nothing more than a conventional operation of a screw thread forming machine and advantage is taken of the accuracies in cutting operations characterizing the operation of such machines. The forming of the thread, at least in so far as its pitch is concerned, is entirely independent of the operator, and, as it is possible to make the lead screw relatively large compared to the small size of the completed work, an extremely high degree of accuracy in the formation of the completed thread may be attained simply by the exercising of reasonable accuracy in the formation of the groove or grooves in the controlling lead screw.

As the same lead screw may be used repeatedly it follows that a large number of dies may be manufactured with the assurance that the threads in each die are facsimiles of the threads in every other die so constructed and there results a uniformity in the corrugation of all of the tubing produced by the use of any of the dies.

Having thus described my invention, I claim:

1. In the art of forming a helical tooth on a substantially cylindrical body, the method which consists in causing a cutting tool to form a helical groove of decreasing pitch with respect to the longitudinal axis of the cylindrical body thereby to form a helical tooth between adjacent turns of the groove, causing the tool to engage a side of said tooth at one end thereof and to repeat its cut along a path parallel to the previous path whereby the trough between adjacent turns at one end is formed of greater length than adjacent the other end axially of the cylinder and with the trough decreasing in axial length from one to the other end.

2. In the art of forming on a cylindrical body, a helical tooth with a progressively decreasing length of trough between succeeding turns of the tooth, the method which consists in rotating a blank element about its axis, causing a tooth groove forming tool to advance axially of the cylindrical blank and at a progressively slower rate per rotary turn of the blank thereby to form a continuous helical groove in blank with a uniformly decreasing pitch and causing said tool to repeat its cutting operation along the same pitch line but offset slightly from its previous path of movement.

3. In a device of the class described, the combination of means for mounting a work blank for rotary movement about an axis, mechanism for rotating said blank, a tool operatively mounted for linear movement parallel to said axis while in operative engagement with the work blank, and control means operatively connected to both the rotary mechanism and the tool to cause a uniform acceleration of said linear movement of

the tool during succeeding units of time defined by the rotary movement of the work blank, and means for indexing the work blank between succeeding linear movements of the tool.

4. In a lathe structure, the combination of means for cutting a helical tooth with the trough therebetween of greater length axially at one end of a member than at the other end, said means including a tool, lead screw controlled means for advancing the tool at a variable velocity and a replaceable lead screw provided with a helical groove of variable pitch controlling said means.

5. A lead screw for controlling the advance of a tool in a lathe construction, comprising a cylindrical body, provided with means for mounting the same for rotary movement about its axis, a surface of the body provided with a nut receiving groove progressively decreasing in pitch from one towards the other end of the screw and the groove at one end terminating in a plane perpendicular to the axis of the cylindrical body.

6. A lead screw for controlling the advance of a tool in a lathe or equivalent machine, said screw comprising a cylinder having a plurality of helical grooves in its surface and each groove adapted to receive a nut advanced by the rotation of the screw, said grooves each having a progressively decreasing pitch from one towards the other end of the screw, the pitch distance between adjacent grooves gradually reducing in length axially of the screw from one towards the other end and all of said grooves merging into each other at said other end.

7. A lead screw for use in controlling a tool advance in a lathe or similar machine, said screw provided with a plurality of nut receiving helical grooves each having a variable pitch, said grooves being spaced apart at one part of the screw and merging into a common groove at another part of the screw.

Signed at New York, in the county of New York and State of New York, this 2nd day of Oct. A. D. 1926.

HERBERT W. TRANTER.
